Atty.

UNITED STATES PATENT OFFICE

WARD W. SLAWSON, OF SOMERVILLE, MASSACHUSETTS

COIN-CONTROLLED TURNSTILE

Application filed April 27, 1928. Serial No. 273,251.

This invention relates to a turnstile of that character in which operation of the turnstile is controlled by a coin and particularly to a turnstile which is normally locked and 5 is unlocked by a coin deposited in a coin box. In apparatus of this character as now constructed and known to me, the coin, after it has unlocked the turnstile, is automatically removed from its operative position, by a 10 portion of the apparatus, and the turnstile is again locked, and remains in this condition until unlocked by another coin.

In apparatus of this character, it is possible to unlock the turnstile by an abnormal 15 coin or device, which remains in its deposited position and is not removed therefrom by the portion of the apparatus which removes the normal coin.

By means of the abnormal coin, the turnstile 20 may be unlocked and be maintained in this condition as long as the abnormal coin remains in its deposited position, thereby allowing any number of persons to pass through the turnstile without paying, until 25 the abnormal coin has been removed.

The present invention has for its object 30 to provide a coin-controlled turnstile in which the turnstile is unlocked and then locked by a normal coin, and is unlocked and then locked by an abnormal coin, with the latter in its unlocking position, with the result that but a single person can pass through the turnstile by the deposit of a coin either 35 normal or abnormal.

In the present instance, the invention is embodied in an electrically controlled turnstile, in which an electromagnet is employed 40 to unlock the turnstile, and is controlled by a second electromagnet or relay, which in turn is controlled by the coin.

In a turnstile of this character, the relay is energized by the coin closing the circuit of said relay, and the latter when energized closes the circuit of the unlocking magnet, 45 which when energized unlocks the turnstile.

Under normal conditions of use, that is, when the circuit of the relay is closed by a normal coin, the latter is dislodged to open the relay circuit when the relay is energized.

Under abnormal conditions of use, that is,

when the circuit of the relay is closed by an abnormal coin, the latter is not dislodged by the relay when energized, but remains in its circuit-closing position, which in the absence of the present invention, would maintain the unlocking magnet energized and thereby keep the turnstile unlocked until the abnormal coin was removed.

In accordance with the present invention, provision is made for taking the relay and thereby the unlocking magnet out of the control of the abnormal coin, so that, when the relay is energized by the abnormal coin, the circuit of the relay is opened at a different point when the relay is energized, which permits the circuit of the unlocking magnet to be opened by the relay and the turnstile to be locked, with the abnormal coin in its circuit-closing position.

To this end, an auxiliary relay is employed 70 which acts to open the circuit of the main relay and to maintain it open as long as the abnormal coin remains in its circuit-closing position.

These and other features of this invention 75 will be pointed out in the claims at the end of this specification.

Fig. 1 is a plan view of a coin-controlled turnstile embodying this invention;

Fig. 2, an elevation of the turnstile shown 80 in Fig. 1;

Fig. 3, a diagrammatic view of a sufficient portion of the apparatus shown in Fig. 1 to enable its operation to be understood, the parts being arranged to illustrate the normal position of the apparatus and about to be operated by a normal coin;

Fig. 4, a view like Fig. 3, illustrating the 85 unlocking of the turnstile by the normal coin and the removal of the latter from its operative position shown in Fig. 3;

Fig. 5, a view like Fig. 4 illustrating the operation with an abnormal coin, and

Fig. 6, a developed view of the movable 90 circuit-controlling members carried by the turnstile.

The mechanical portion of the apparatus is 95 and may be such as now used in subways, railway stations and other places where entrance is gained by depositing in a receptacle 100

a coin or other device indicative of the charge for admission. In the present instance, only a sufficient portion of the apparatus is illustrated to enable the invention to be readily understood.

10 represents a rotatable turnstile which co-operates with a rail 12 to form a passageway 13 through which persons pass after depositing a coin, or like device indicative of the charge for admission. For the present purposes, the coin may be considered as a dime, and that the turnstile is used at the entrance to a railway station, as, for instance, a subway.

15 Located near the rail 12 is a coin box 15 into which the dime, represented by the circle 16 in Fig. 3, is deposited by a person passing into the passageway 13 in the direction indicated by the arrow in Fig. 1.

20 The coin box 15 contains a relay 17, which will be hereinafter referred to as the main relay, and said main relay is included in an electric circuit provided with yielding metal fingers or contact members 20, 21 spaced apart and located in the coin box 15 below a slot 22 therein, and arranged to be electrically connected together by the coin 16 after the latter has passed into the coin box.

25 The fingers 20, 21 co-operate with the coin 16 to form a circuit controller for the main relay 17, which circuit controller will be hereinafter termed the coin-circuit controller.

30 The main relay 17 functions to control the operation of an electromagnet 23, which functions to unlock the turnstile 10 and permit the latter to be rotated a quarter-turn by the person who has deposited the coin 16 in the coin box, which coin may be designated the normal coin. The shaft 24 of the turnstile 40 is provided with contact members 25 corresponding in number to the number of arms of the turnstile, which is four as herein represented.

35 Each of these contact members 25 is adapted to be brought into engagement with a pair of contact arms 26, 27 spaced apart and suitably supported within the hollow standard or upright 28 upon which the turnstile is rotatably mounted. Each movable contact member 25 co-operates with the pair of contact members 26, 27 to form a circuit controller for the main relay 17, and each of these circuit controllers may be designated the turnstile-circuit controller, which is closed when the turnstile is in its normal or locked position or condition, but which is opened when the turnstile is rotated to permit the depositor of the coin to pass through the turnstile.

40 With the turnstile in its locked position, the circuit of the main relay 17 is closed at the turnstile by the circuit controller 25, 26, 27, and is open at the coin-circuit controller.

45 When the proper or normal coin 16 is deposited into the coin box 15, the circuit of

the relay 17 is completed by the normal coin 16 engaging the contact members 20, 21, as represented in Fig. 3.

The circuit of the main relay 17 being thus completed energizes the main relay, which attracts its armature and closes the circuit of the unlocking electromagnet 23, which unlocks the turnstile and permits the depositor of the coin 16 to rotate the turnstile a quarter-turn and pass through the passage 13 and enter the station. The main relay 17 is preferably made as a solenoid and its armature or core is represented by the line 30 in Fig. 3.

The armature 30 is provided with a movable contact member 31 which co-operates with terminals or contact members 32, 33 to form a circuit controller for the unlocking magnet 23. When the main relay is energized, the circuit of the unlocking magnet 23 is completed at the circuit controller 31, 32, 33, and the turnstile 10 is unlocked. The mechanical mechanism of the turnstile is such that when the main relay 17 is energized, the normal coin 16 is ejected or caused to pass between the contact fingers 20, 21 and fall to the bottom of the coin box, thereby opening the circuit of the main relay at the coin-circuit controller. This would deenergize the locking magnet 23 and cause the turnstile to be locked if provision were not made to provide a circuit for maintaining the main relay energized independently of the coin-circuit controller. This is accomplished by a contact member 34 on the armature 30 of the main relay, co-operating with terminals or contact members 35, 36 to complete a circuit for the main relay as will be described.

50 As soon as the circuit of the main relay 17 is completed by the coin 16, the main relay is energized and the auxiliary circuit therefor is completed at the circuit controller 34, 35, 36 before or at or about the time the coin 16 opens the initial circuit for the main relay by passing out of contact with the terminals 20, 21.

55 This condition of the circuits of the main relay 17 and of the unlocking magnet 23 is represented in Fig. 4.

The circuit through the main relay may be traced as follows: from the battery 38 or other source of current by wire 60 to the turnstile-circuit controller 26, 25, 27, thence by wire 39 to main relay 17, through the latter and by wires 40, 41 and circuit controller 35, 36 and wire 42 to ground 43, thence by wire 44 back to the battery 38.

60 The circuit of the unlocking magnet 23 may be traced as follows: From the battery 38 by wire 45 unlocking magnet 23, wire 46, circuit controller 32, 31, 33, wires 47, 42 to ground 43 and thence by wire 44 back to battery.

65 The main relay 17 is now under control of the turnstile-circuit controller, which latter is opened when the depositor of the coin turns

the turnstile sufficiently to move the contact member 25 out of engagement with the contact members 26, 27.

Deenergizing of the main relay 17 as just described, allows the armature 30 to drop and open the circuit of the unlocking magnet 23 and permit the turnstile, by means of the next contact member 25, to close the circuit of the main relay at the turnstile-circuit controller, and place said main relay circuit in condition to be completed by the next coin deposited, the turnstile being at such time locked.

The apparatus operates in the manner above described, providing the coin is a proper or normal one, which can be dislodged from contact with the contact fingers or members 20, 21 when the main relay is energized. If, however, there is deposited in the coin box, an abnormal coin or metal disk approximating the dimensions of the normal coin, so as to permit it to be deposited in the coin box and engage the contact members 20, 21, but is of such size or construction as not to be dislodged when the main relay is energized, such abnormal coin would maintain the circuit of the main relay closed at the coin-circuit controller.

Under these conditions, the circuit of the locking magnet 23 is initially closed when the circuit of the main relay is completed at the coin-circuit controller, is momentarily opened at the circuit controller 31, 32, 33, when the main relay circuit is opened at the turnstile-circuit controller 25, 26, 27, and again closed when the main relay is again energized, by the closing of the turnstile-circuit controller, which occurs when the turnstile has been rotated a quarter-turn by the deposit of the abnormal coin passing through the turnstile.

It will thus be seen that an indefinite number of persons may pass through the turnstile as long as the coin-circuit controller remains closed by the abnormal coin, thereby occasioning a decided loss of revenue.

The present invention has for its object to avoid such loss of revenue, and to this end, provision is made for deenergizing the main relay independently of the coin-circuit controller after said main relay has been initially energized by the abnormal coin, and to maintain said main relay deenergized, as long as the coin-circuit controller is closed by the abnormal coin.

Inasmuch as the circuit of the unlocking magnet 23 is open as long as the main relay is deenergized, the turnstile will remain locked and thereby be prevented from being turned until the abnormal coin has been removed by a duly authorized person.

To effect these desirable results, the circuit of the main relay 17 is provided with a second circuit controller, comprising a stationary contact member 50 and a co-operating mov-

able contact member 51, which latter is connected with the armature or core 52 of an auxiliary solenoid or relay 53, which latter is included in a circuit governed in part by the coin-circuit controller and in part by a circuit controller actuated by the main relay and comprising a movable contact member 54 which is attached to the core or armature 30 of the main relay, and co-operating contact members 55, 56.

As represented in Figs. 3, 4 and 5, the auxiliary relay 53 has one end of its coil connected by wire 57 with the member 20 of the coin-circuit controller, and has the other end of its coil connected by wire 58 with the stationary contact member 55 of the circuit controller 55, 54, 56, the stationary contact member 56 being connected by wires 59, 45 to the battery 38 or other source of current, which is represented as connected through the ground 43 with the member 21 of the coin-circuit controller.

Under normal conditions, the coin-circuit controller is open and the main and auxiliary relays 17, 53 are deenergized. The circuit controller 51, 50 governed by the auxiliary relay 53 is closed and the circuit controller 54, 55, 56 governed by the main relay is opened.

It will thus be seen that the main relay 17 is included in a circuit provided with three circuit controllers, one of which is the coin-circuit controller, the second the circuit controller 51, 50 governed by the auxiliary relay 53, and the third the circuit controller 54, 55, 56 governed by the turnstile.

Under normal conditions, the coin-circuit controller is open and the other two circuit controllers are closed.

When a normal or an abnormal coin is deposited in the coin box 15, the circuit of the main relay 17 is completed. This circuit is represented by the heavy black lines in Fig. 3 and may be traced as follows: from the battery 38 by wire 60, turnstile-circuit controller 26, 25, 27, wire 39, main relay 17, wire 40, circuit controller 50, 51, wires 61, 57, coin-circuit controller 20, 16, 21, wire 62, ground 43 and wire 44 back to the battery.

The main relay 17 is energized and closes the three circuit controllers, to wit: the circuit controller 34, 35, 36 for the circuit of the main relay independently of the coin-circuit controller; the circuit controller 31, 32, 33 for the circuit of the unlocking magnet 23; and the circuit controller 54, 55, 56 for the auxiliary relay 53.

The circuit for the main relay 17 independently of the coin-circuit controller is represented by heavy black lines in Fig. 4, and may be traced as follows: from the battery 38 by wire 60, turnstile-circuit controller 26, 25, 27, wire 39, main relay 17, wires 40, 41, circuit controller 34, 35, 36, wire 42, ground 43 and wire 44 back to the battery 38.

The circuit through the unlocking magnet 130

23 is also represented by heavy black lines in Fig. 4 and may be traced as follows: from the battery 38 by wires 60, 45, unlocking magnet 23, wire 46, circuit controller 32, 31, 33, wires 47, 42, ground 43 and wire 44 back to the battery.

The circuit through the auxiliary relay 53 is represented by heavy black lines in Fig. 5 and may be traced as follows: from the battery 38 by wires 60, 45, 59, circuit controller 56, 54, 55, wire 58, auxiliary relay 53, wire 57, circuit controller 20, 16, 21, ground 43 and wire 44 back to the battery.

This circuit for the auxiliary relay may be termed the energizing circuit therefor and is closed when the main relay 17 is energized by the deposit of the abnormal coin 16^a represented in Fig. 5. It would be opened by deenergizing the main relay 17 when the depositor of the abnormal coin passes through the turnstile; if provision were not made to provide a circuit for the auxiliary relay independently of the circuit controller 54, 55, 56 operated by the main relay. To this end the auxiliary relay 53 operates a second circuit controller, comprising a movable member 70 attached to the core 52 of said auxiliary relay and a stationary contact member 71, the movable member 70 being connected by wire 72 to the wire 59 of the energizing circuit, and the stationary member 71 being connected by wire 73 to the wire 58 of said energizing circuit. The circuit controller 70, 71 is normally open and is closed when the energizing circuit for the auxiliary relay 53 is completed by the circuit controller 54, 55, 56 when the main relay 17 is energized.

The circuit for the auxiliary relay 53 including the circuit controller 70, 71 may be designated the maintaining circuit for the auxiliary relay.

It remains closed as long as the abnormal coin 16^a remains in contact with the contact members 20, 21.

This maintaining circuit is represented in Fig. 5 by heavy black lines and may be traced as follows: from the battery 38 by wires 60, 45, 59, 72, circuit controller 70, 71, wires 73, 58, relay 53, wire 57, coin controller 20, 16^a, 21, wire 62, ground 43, wire 44 back to the battery. This maintaining circuit keeps the auxiliary relay 53 energized independently of the control member 54 as long as the coin-circuit controller is closed by the abnormal coin 16^a, and keeps the circuit of the main relay 17 open at the controller 51, 50, and the main relay being thus deenergized keeps the circuit of the unlocking magnet 23 open at the controller 31, 32, 33, thereby maintaining the turnstile locked after the depositor of the abnormal coin has passed through the turnstile.

When the circuit of the main relay 17 is closed by the abnormal coin 16^a, the controller members 34, 31, 54 are moved into their

closed positions as shown in Fig. 5; the turnstile is unlocked and the depositor of the abnormal coin 16^a can pass through the turnstile. On passing through, the turnstile is rotated and the contact 25 which engages the contact members 26, 27 is moved out of engagement with the latter, and the circuit of the main relay 17 is momentarily opened and then closed at the turnstile by the next adjacent contact 25.

When the circuit of the relay 17 is momentarily opened at the turnstile, the said relay is deenergized, and the controller members 34, 31, 54 are moved into their open position shown in Fig. 3, but the auxiliary relay 53 is not deenergized by the opening of the controller member 54, as the circuit of the auxiliary relay 53 is maintained closed by the abnormal coin 16^a and by the controller member 70.

When the circuit of the main relay 17 is reestablished, as shown in Fig. 5, by the depositor of the abnormal coin 16^a rotating the turnstile 10 a quarter-turn, the circuit of the main relay is open at the controller 50, 51 and the turnstile is locked and maintained locked and put out of commission until the abnormal coin 16^a is removed by an authorized person.

In this manner other persons in collusion with the depositor of the abnormal coin are prevented from passing through the turnstile.

The movable member 54 of the circuit controller for the auxiliary relay, will be arranged to close the circuit of said relay, after the movable members 31 and 34 on the core 30 of the main relay have completed their circuits.

The turnstile-operating construction including the mechanism for locking the turnstile and the unlocking magnet 23 co-operating with said locking mechanism is located in the hollow casing or pedestal 28 and may be such as shown in United States Patent No. 1,655,501 dated January 10, 1928, to which reference may be had, as such mechanism is not herein claimed.

The main relay 17, the circuit controllers actuated thereby, the auxiliary relay 53, the circuit controllers actuated by it, and the coin-circuit controller may be located in the coin box 15, as indicated by dotted lines in Fig. 2.

From the above description, it will be observed that the turnstile is automatically controlled by the deposited coin, and the services of an attendant are not required, and it will further be observed that the turnstile will continue to function and permit the depositors to pass in a continuous manner as long as each depositor places a normal coin in the coin box, but that the turnstile is rendered inoperative and put out of commission, when an abnormal coin is deposited in the coin box.

As a result, railways and other users of

turnstiles embodying this invention are prevented from suffering substantial losses.

One embodiment of the invention is herein shown, but it is not desired to limit the invention to the particular embodiment shown.

What is claimed is:

1. The combination with a turnstile normally locked against rotation in one direction, of an electromagnet for unlocking said turnstile, a circuit controller governing the operation of said unlocking magnet, a main relay governing the operation of said circuit controller, a circuit for said main relay provided with a coin-controlled circuit controller and with a second circuit controller operated by said turnstile, a circuit controller operated by the main relay to establish a circuit for the latter and place the main relay under control of the turnstile-circuit controller, an auxiliary relay, a circuit controller operated by said auxiliary relay and included in the coin-controlled circuit of said main relay and normally closed, a circuit controller operated by said main relay and operating to energize said auxiliary relay in conjunction with said coin-circuit controller, a second circuit controller operated by said auxiliary relay and normally open, said auxiliary relay when energized acting to operate the normally closed circuit controller to open the same and de-energize the main relay with the coin-circuit controller closed, and acting on the normally open circuit controller to close a circuit through the auxiliary relay and maintain the latter energized with the energizing circuit for the auxiliary relay closed at the coin-circuit controller and opened at the circuit controller operated by the main relay.

2. The combination with a turnstile normally locked against rotation in one direction, of an electromagnet for unlocking said turnstile, a circuit controller governing the operation of said unlocking magnet, a main relay governing the operation of said circuit controller, a circuit for said main relay provided with a coin-circuit controller and with a second circuit controller normally closed, and an auxiliary relay governed by the main relay and operating to open said second circuit controller and thereby open the circuit of the main relay with the latter circuit closed at the coin controller.

3. The combination with a turnstile normally locked against rotation in one direction, of an electromagnet for unlocking said turnstile, a circuit controller governing the operation of said unlocking magnet, a main relay governing the operation of said circuit controller, a circuit for said main relay provided with a coin-circuit controller and with a second circuit controller normally closed, an auxiliary relay governed by the main relay and operating to open said second circuit controller and thereby open the circuit of the main relay with the latter circuit

closed at the coin controller, and a second circuit controller operated by the auxiliary relay to maintain a circuit therefor in conjunction with the coin-circuit controller when the energizing circuit of the auxiliary relay is opened by deenergizing of the main relay.

4. The combination with a turnstile, of an electromagnet controlling the operation thereof, a main relay controlling the operation of said electromagnet, a coin-circuit controller governing the operation of said main relay and an auxiliary relay also governing the operation of said main relay and non-responsive to the operation of said coin-circuit controller by a normal coin to affect the circuit of the main relay and responsive to the operation of the coin-circuit controller by an abnormal coin to affect the circuit of the main relay.

5. The combination with a turnstile normally locked against rotation in one direction, of means for unlocking said turnstile, means responsive to a normal coin for controlling said unlocking means to permit the turnstile to be unlocked with the normal coin in its operative position and to be again locked when said normal coin has been removed from its operative position, and means operated by said controlling means for taking the latter out of the control of an abnormal coin and permitting the turnstile to be locked with the abnormal coin in its operative position.

6. The combination with a turnstile, of an electromagnet controlling the operation thereof, a coin-circuit controller governing the operation of said electromagnet and responsive to a normal coin to render said electromagnet effective upon said turnstile and a relay responsive to an abnormal coin to render the electromagnet ineffective upon said turnstile and maintain it ineffective as long as the relay remains under the control of said abnormal coin.

In testimony whereof, I have signed my name to this specification.

WARD W. SLAWSON.
